(57) **CLAIM**

We claim the ornamental design for a monitor having home network indicating image design displayed thereon, as shown and described.

DESCRIPTION

The file of this patent contains at least one drawing executed in color. Copies of this patent with color drawings will be provided by the Office upon request and payment of the necessary fee.

FIG. 1. is a top front perspective view of a monitor having a home network indicating image design displayed thereon showing our new design.

FIG. 2. is a front elevational view thereof; and,

FIG. 3. is a front enlargement of the image area shown in FIG. 2, shown separately for clarity of illustration.

The areas shown in broken line are for illustrative purposes only and form no part of the claimed design.
